COIN-OPERATED TYPEWRITER CONTROL
APPARATUS

Jesse B. Graham, La Mesa, Calif.

Application November 13, 1944, Serial No. 563,136

3 Claims. (Cl. 197—193)

1

My invention relates to a coin operated typewriter control apparatus, more particularly to an apparatus for limiting the use of a typewriter over certain periods of time with the insertion of coins therein, and the objects of my invention are:

First, to provide an apparatus of this class with a coin slide which is pressed inwardly with a coin therein and returned for automatically releasing the typewriter keys and starting an escapement timing device which controls the use interval of the typewriter;

Second, to provide an apparatus of this class which is so arranged that the use of the typewriter cannot be had without considerable tampering which could not ordinarily be carried on in a public place;

Third, to provide an apparatus of this class which is very reliable and accurate in operation;

Fourth, to provide an apparatus of this class in which a register tabulates the individual use intervals during the operation of said apparatus;

Fifth, to provide an apparatus of this class which is readily adaptable for use in connection with various makes of typewriters;

Sixth, to provide an apparatus of this class in which a register provides the owner with an accurate check on the use of said apparatus in comparison with the number of coins deposited therein; and

Seventh, to provide an apparatus of this class which is very simple and economical of construction, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference there on which form a part of this application in which:

Figure 1 is a transverse sectional view of the typewriter control apparatus showing by dash lines varying positions of parts and portions thereof taken from the line 1—1 of Fig. 2; Fig. 2 is a fragmentary sectional view taken from the line 2—2 of Fig. 1; Fig. 3 is a sectional view taken from the line 3—3 of Fig. 4 and Fig. 4 is a fragmentary plan sectional view taken from the line 4—4 of Fig. 1 and Fig. 5 is a fragmentary bottom plan view of the mechanism taken from the line 5—5 of Fig. 3.

2

Similar characters of reference refer to similar parts and portions throughout the several views of the drawings:

The table top 1, table top side members 2 and 3, table bottom member 4, table top lock 5, mechanism casing 6, mechanism supporting plates 7, cam supporting arm 8, cam 9, latch 10, trip lever 11, typewriter control levers 12 and 13, lever lock member 14, coin slide engaging member 15, retaining link 16, springs 17, 18, 19, 20 and 22, coin receiver assembly 23, coin receiver slide 24, timing mechanism 25, latch control lever 26, register 27, and the link 28 constitute the principal parts and portions of my typewriter control apparatus.

The table top 1 is a flat plate-like member having a substantially horizontal upper surface 1a on which a typewriter, as indicated by dash line A is positioned. This typewriter A is secured on the table top 1 by means of the bolt 1b, as shown best in Fig. 1 of the drawings. This table top 1 at its one side edge is provided with a hinge 1c which maintains the table top 1 in hinged connected relation with the table side member 3. The opposite side edge of the table top 1 is connected with the table top side member 2 by means of the table top lock 5. This lock 5 is a conventional tumbler lock and is provided with a shiftable arm 5a which engages a slotted portion 2a in the metal plate 2b secured in connection with the table top side member 2, all as shown best in Fig. 1 of the drawings. Connected with the table top side members 2 and 3 in opposed relation to the table top 1 is the table bottom member 4 forming an enclosed casing in which the mechanism casing 6 is positioned. This mechanism casing 6 is a rectangular box-like structure in which the mechanism supporting plate 7 is enclosed. As shown in Fig. 2 of the drawings, the top portion 6a of the mechanism casing 6 is provided with a slotted portion 6b therein through which the typewriter control lever extends. The mechanism supporting plate 7 is a flat member preferably made of sheet metal or the like, and this mechanism supporting plate 7 retains the principal operating mechanism of my coin operated typewriter control apparatus. Secured on the lower side of this mechanism supporting plate 7 is the timing mechanism 25 which consists of substantially conventional clockworks parts. This timing mechanism 25 is provided with a main operating shaft 25a on which the cam supporting arm 8 is rigidly secured by means of the collar 25b and set screw 25c. Secured on the opposite end of the operating shaft

25 is a disk 25d provided with a notch 25e in its periphery engaged by a pin 26a of the latch control lever 26 which is pivoted on the pin 26b in connection with the timing mechanism 25. It will be here noted that the conventional clock-works mechanism in the casing 25f controls the movement of the operating shaft 25a. Secured on the opposite end of the cam supporting arm 8 is the cam 9 which extends downwardly toward the plate 7, as shown best in Fig. 3 of the drawings. The trip lever 11 is pivotally mounted on the pin 11b in connection with the plate 7 and is provided with an upwardly extending pin 11a to which is connected the tension spring 19 which is secured at its opposite end by the pin 19a in connection with the plate 7, tending to hold the trip lever 11 in the dash line position as shown in Fig. 4 of the drawing. The trip lever 11 is maintained in the solid line position, as shown in Fig. 4 of the drawings by the latch 10 which is pivotally mounted on a bracket 10a in connection with the plate 7, as shown best in Fig. 3 of the drawings. This latch 10 is provided with a notch portion 10b and an opposed tooth portion 10c which engages the trip lever 11 through the slot 7a in the plate 7, as shown best in Figs. 3 and 4 of the drawings. The latch control lever 26 is provided with an extending edge portion 26c engageable with the notch portion 10b of the latch 10, as shown best in Figs. 3 and 5 of the drawings. The extending end of the trip lever 11 is arranged to engage the lower end of the typewriter control lever 12, as shown best in Fig. 4 of the drawings.

The register 27 is secured on the plate 7 and is a conventional numerical register arranged to register the number of times the trip lever 11 is forced from the dash line position to the solid line position indicating the number of time intervals occurring during the use of my typewriter control apparatus.

The link 28 is connected to the arm 27a on the register 27, as shown best in Figs. 3 and 4 of the drawings. This register 27 is the conventional device arranged to register numbers from zero to 99,999.

The typewriter control lever 12 is pivotally mounted on a bracket 12a which is secured on the upper side of the mechanism casing 6 as shown best in Figs. 1 and 2 of the drawings. The lower end of this typewriter control lever 12 extends through the slotted opening 7b in the mechanism supporting plate 7, as shown best in Figs. 1 and 2 of the drawings. The lower end of the typewriter control lever 12 is engageable with the lever lock member 14 which is a pivotally mounted member pivotally supported on the pin 14a, as shown best in Fig. 4 of the drawings. The upper end of the typewriter control lever 12 is provided with an angularly disposed edge portion 12b which engages an outwardly extending angular portion 13a of the typewriter control lever 13. This typewriter control lever 13 is pivotally mounted on a pin 13b in connection with a bracket 13c which is secured on the upper side of the table top 1, all as shown best in Figs. 1 and 2. As shown in Fig. 2 of the drawings the typewriter control lever 12 extends through a slotted portion 1d in the table top 1 and the bracket 13c is mounted at one side thereof. Enclosing the bracket 13c and the lower portion of the typewriter control lever 13 is a box-like casing 13d. This casing 13d is provided with a slotted opening in its upper side designated 13e through which the typewriter control lever 13

extends. The upper end portion 13f of the typewriter control lever 13 engages the typewriter key control bar B of the typewriter as shown by dash line A in Fig. 3 of the drawing. This typewriter key control bar B is substantially L-shaped in cross section and is arranged to engage the notch portion C' of the typewriter key lever C for locking the typewriter keys in certain position for rendering the typewriter inoperative. The lever lock member 14 is pivotally mounted on the pin 14a in connection with the mechanism supporting plate 7 and is pivotally mounted over the slotted portion 7b in the mechanism supporting plate 7, as shown best in Fig. 4 of the drawings. This lever lock member 14 is provided with opposed latch portions 14b and 14c, which are formed on the radius described from the axis of the pin 14a. These latch portions 14b and 14c are spaced sufficiently to permit the lever 12 to pass therebetween, all as shown best in Fig. 4 of the drawings. The pin 14d rigidly connected to the lever lock member 14 is positioned in the slotted portion 16a of the retaining link 16 and the spring 17 engages this pin 14d and is connected at its opposite end to the pin 16b in connection with the retaining link 16. This retaining link 16 is pivotally mounted by means of the pin 16c to the coin slide engaging member 15, all as shown best in Fig. 4 of the drawings. This coin slide engaging member 15 is L-shaped in cross section, as shown in Fig. 3 of the drawings and is pivotally mounted on a pin 15a in connection with the plate 7. The stop 15b is secured to the plate 7 and is engageable with the lower edge of the coin slide engaging member 15, all as shown best in Fig. 4 of the drawings. The retaining link 16 is provided with a notched portion 16d arranged to clear the pin 15a when in the dash line position, as shown in Fig. 4 of the drawings. The spring 18 is secured on the plate 7 at one end by means of the pin 18a and is connected at its opposite end to the coin slide engaging member 15 tending to hold the same in the solid line position, as shown in Fig. 4 of the drawings. As shown in Fig. 1 of the drawings, the typewriter control lever 12 is connected with the tension spring 22. This tension spring 22 is secured to a pin 22a which extends from the lower side of the top portion 6a of the mechanism casing 6. This tension spring 22 tends to force the lower end of the typewriter control lever 12 away from the lever lock member 14. The coin receiver 23 is the conventional coin receiver and selecting device provided with a coin receiver slide 24, which is of the reciprocably mounted type having a coin conveying portion 24a therein, as shown best in Fig. 4 of the drawings. This coin receiver 23 is also provided with a selection magnet 23a for use in detecting spurious coins of metal subject to magnetic attraction. The outer end portion 24b of the coin receiver slide 24 forms a handle for the manual reciprocable operation thereof when a coin is positioned in the conveyer portion 24a, all as shown best in Fig. 4 of the drawings. This coin receiver 23 is provided with a flange 23b which is secured to the table top 1 side member 2 all as shown best in Fig. 4 of the drawings. As indicated by dash lines in Fig. 4 of the drawings, the coin receiver slide 24 is arranged to engage the coin slide engaging member 15 and the cam 9 for shifting the cam supporting arm 8, all as indicated by dash lines in Figs. 4 and 5 of the drawings.

The operation of my coin operated typewriter control apparatus is substantially as follows: When a person desires to use and operate the typewriter, as shown by dash lines A in Fig. 1 of the drawings, he may proceed as follows:

A proper coin must be inserted in the conveyer portion 24a of the coin receiver slide 24. Then the coin receiver slide 24 is pressed inwardly to the limit of its travel, as indicated by dash lines in Fig. 4 of the drawings. The coin positioned in the conveyer portion 24a is ejected from the coin receiver 24 and falls into the inner side of the table on the table bottom member 4. As the coin receiver slide 24 passes inwardly to the dash line position E, it engages the coin slide engaging member 15 and pivots the same on the pin 15a to the dash line position as shown in Fig. 4 of the drawing. This coin slide engaging member 15 forces the retaining link 16 into the dash line position, as shown in Fig. 4 of the drawings, shifting the lever lock member 14 into the dash line position maintaining the lower end of the typewriter control member 12 by means of the latch portion 14b. Thus the typewriter control member 12 is maintained in the dash line position, as shown in Fig. 1 of the drawings limiting the use of the typewriter.

The coin receiver slide 24 when passing inwardly to the dash line position E also engages the cam 9 shifting the cam supporting arm 8 to the dash line position H and carrying with it the trip lever 11 which is caught by the latch 10, all as shown best in Fig. 4 of the drawings. During the passage of the cam 9 from the solid line position to the dash line position, as shown in Fig. 4 of the drawings, the timing mechanism shaft 25a rotates carrying with it the plate 25d and shifting the latch control lever 26 to the dash line position, as shown in Fig. 5 of the drawings, whereby the portion 26c thereof passes from the notch 10b of the latch member 10 to the full line position, as shown in Fig. 3 of the drawings, holding the latch member 10 in engagement with the trip lever 11. It will be here noted that when the cam member 9 is shifted to the dash line position, as shown in Fig. 4, the rotation of the main shaft 25a cocks the main spring in the timing mechanism 25 which runs for approximately 30 minutes during which time the cam supporting lever 8 passes from the dash line position to the solid line position, as shown in Fig. 4 of the drawings. After the coin receiver slide 24 is pressed inwardly, it is retracted by the spring 24c permitting the coin slide engaging member 15 together with the retaining link 16 and the lever lock member 14 to shift backwardly toward the solid line position, as shown in Fig. 4 of the drawings. As the latch portion 14b of the lever lock member 14 passes backwardly it releases the lower end of the typewriter control lever 12 whereby the type control bar B and the lever 13 shift to the solid line position, as shown in Fig. 1 of the drawings permitting the operation of the typewriter A. When the cam supporting lever 8 shifts backwardly toward the solid line position, it is controlled by the timing device 25 in connection with the shaft 25a. When thirty minutes have passed the plate 25d, as shown in Fig. 5 of the drawings turns with the shaft 25a shifting the notched portion 25e and permitting the pin 26a of the lever 26 to fall therein. The spring 20 forces the latch control lever 26 to the solid line position in which the portion 26c of the latch control lever 26 rests over the notch 10b of the latch 10. It will be obvious that the tension of

the spring 19 in connection with the trip lever 11 acts on a moment arm extending from the axis of the latch 10 to the plane of the trip lever 11 which positively aids gravity and shifts the latch 10 out of engagement with the trip lever 11 whereby the end portion of the trip lever 11 engages the typewriter control lever 12 forcing the same into the lever lock member 14 in engagement with the latch portion 14c thereof whereby the typewriter control levers 12 and 13 together with the type control bar B are shifted to the dash line position, as shown best in Fig. 1 of the drawings limiting the use of the typewriter until another coin is deposited in the coin slide 24.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a coin operated typewriter control apparatus of the class described, the combination consisting of a reciprocably mounted coin receiving slide, a pivotally mounted arm having cam means in connection therewith near the end thereof and in the path of said coin receiving slide at its one end arranged to shift said arm with the inward movement of said coin receiving slide, a shaft connected with and forming the axis of said arm, escapement timing mechanism in connection with said shaft and operable therewith, a pivotally mounted trip lever in the path of said pivotally mounted arm engageable with the cam means thereof, a latch in the path of said trip lever and arranged to engage the same, a spring tending to hold said trip lever in engagement with said latch, and a latch control lever operated by said timing mechanism arranged to relieve said latch.
2. In a coin operated typewriter control apparatus of the class described, the combination consisting of a reciprocably mounted coin receiving slide, a pivotally mounted arm having cam means in connection therewith near the end thereof and in the path of said coin receiving slide at its one end arranged to shift said arm with the inward movement of said coin receiving slide, a shaft connected with and forming the axis of said arm, escapement timing mechanism in connection with said shaft and operable therewith, a pivotally mounted trip lever in the path of said pivotally mounted arm engageable with the cam means thereof, a latch in the path of said trip lever and arranged to engage the same, a spring tending to hold said trip lever in engagement with said latch, a latch control lever operated by said timing mechanism arranged to relieve said latch, a typewriter control lever in the path of said trip lever and a lever lock member in the path of said typewriter control lever having opposed latch portions pivotally mounted relatively to said typewriter control lever and arranged to engage the same.
3. In a coin operated typewriter control apparatus of the class described, the combination consisting of a reciprocably mounted coin receiving slide, a pivotally mounted arm having cam means in connection therewith near the end thereof and in the path of said coin receiving slide at its one end arranged to shift said arm

with the inward movement of said coin receiving slide, a shaft connected with and forming the axis of said arm, escapement timing mechanism in connection with said shaft and operable therewith, a pivotally mounted trip lever in the path of said pivotally mounted arm engageable with the cam means thereof, a latch in the path of said trip lever and arranged to engage the same, a spring tending to hold said trip lever in engagement with said latch, a latch control lever 10 operated by said timing mechanism arranged to relieve said latch, a typewriter control lever in the path of said trip lever, a lever lock member in the path of said typewriter control lever having opposed latch portions pivotally mounted relatively to said typewriter control lever and arranged to engage the same, a longitudinally yieldable retaining link in connection with said

lever latch member and a coin slide engaging member pivotally connected with said retaining link whereby said typewriter control lever is held in position within a latch portion of said lever lock member when said coin slide engaging member is engaged by said coin receiving slide.

JESSE B. GRAHAM.
